FIG. 1 is a front perspective view of my dual plug cleaner.

FIG. 2 is a side elevational view of my dual plug cleaner.

FIG. 3 is a rear elevational view of my dual plug cleaner.

The back is planar.

The characteristic feature of my design resides in the elongated front panel opening for the dual plug in combination with the instrumentation layout as shown.

What I claim is:

A design for a dual plug cleaner, as shown and described.
